DOOR STOP

Anton Van Veen, Canton Center, and Kenneth B.
Noble, Branford, Conn.

Application July 13, 1946, Serial No. 683,496

4 Claims. (Cl. 16—49)

1

This invention relates to door closers of the type generally actuated by springs and adapted to close a door through the medium of levers or arms pivotally connected to one another and secured between the door closer and the door frame, the angular relationship of the arms varying in accordance with the degree of opening of the door. More particularly, the present invention relates to a device adapted for use in conjunction with such types of door closers to arrest and prevent the door closing movement of the arms and thereby cause the door to remain open at a desired degree.

An aim of the invention is to provide a device which will be installable upon a door closer of the type having pivoted arms and which will hold a door open in any desired position for purposes of ventilation or other reasons without the necessity for the use of chocks, wedges, foot stops, or other conventional devices.

A further aim of the invention is to provide a device which can be connected to conventional automatic door closers of the type having arms and which may be actuated mechanically to oppose the force of the spring urging the arms into door closing movement and thereby to prevent the closing of the door and hold it open in a desired position.

A still further aim of the invention is to provide a simple and effective mechanical device which may be attached to the arms of a conventional door closer of this type and which is easily and quickly operable to "freeze" the door at any desired degree of opening, but which will be automatically released from operation by moving the door to a greater degree of opening.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a top plan view showing a door closer mounted on a door and with the door held in partially open position by our device;

Fig. 2 is a cross sectional detail view taken on line 2—2 of Fig. 1;

Fig. 3 is a top plan view similar to Fig. 1 but with the door fully closed;

Fig. 4 is a detail side view showing the catch plate in inoperative position with respect to the rod;

2

Fig. 5 is a detail side view showing the catch plate in operative position with respect to the rod;

Fig. 6 is a top plan view similar to Fig. 1 but showing a slightly different embodiment of the present invention;

Fig. 7 is a cross sectional detail view taken on line 7—7 of Fig. 6 but with the relation of the parts somewhat distorted in the interests of clarity;

Fig. 8 is a top plan view similar to Fig. 7 but with the door fully closed;

Fig. 9 is a detail cross sectional view taken on line 9—9 of Fig. 8; and

Fig. 10 is a cross sectional detail view taken on line 10—10 of Fig. 8.

Referring to the drawings, there is illustrated a door closer A of a conventional type which is secured to a door B. The door closer A may be of any suitable type, that shown consisting of a casing 5 enclosing a spindle 6 driven by a spring (not shown) enclosed in the casing. The casing 5 is generally filled with hydraulic fluid which operates in conjunction with suitable mechanism to cushion the action of the spring upon the spindle in such manner that the door will be gradually returned to closed position. Mechanism may be included which permits a sharp increase in the action of the spring toward the end of the closing movement of the door in order to snap the door shut. A lever or arm 10 is pivoted to the spindle 6 at one end and to a second lever or arm 11 at the other end, as at D, the arm 11 being secured to the door frame C. The spring 35 in the casing 5 is adapted to urge the arm 10 in a direction to close the door or, in the present illustrative drawings, in a counterclockwise direction. The opening and closing of the door changes the angular position of the arms relative to one another and, in particular, as shown by Fig. 3, the arms are forced together by the door closing action of the spring. It is the purpose of our invention to provide means for preventing the arms from coming together and

thereby arresting the movement of the door at any point along its arc of travel. Generally, our device consists of a rod or bar pivotally secured at one end to one arm of the door stop and adapted to slide freely through a catch member secured to the other arm of the door stop. Mechanical means are provided for engaging the rod and catch member with one another at a desired position, the engagement being such as to jam the rod against movement and thereby prevent the arms from coming together.

More particularly, referring to Fig. 1, one embodiment of our invention comprises a sleeve 12 firmly secured to one arm 11 of a door closer as by screws 13. Pivotally secured to the sleeve 12, as at 14, is a rod or bar 15 which extends across the other arm 10 of the door closer. Clamped on the arm 10 by screws 19 and a plate 18 is a catch support 17. The member or support 17 is provided on its upper surface with bosses 20 and 21 between which is mounted, on a pivot 23, a catch member 24. The catch member or latch 24 has an opening 25 through which the rod 15 extends and in which the rod normally slides freely. Extending forwardly from the lower end of the latch 24 and disposed at right angles to the member 24 are lugs 26 which are adapted to engage the support 17 so as to limit forward swinging movement of the latch to the upright position shown in Fig. 4. Extending rearwardly from latch 24 is an upwardly inclined trip lever or arm 27 to the end of which is fastened a string or wire 28 which hangs down the side of the door. When the string 28 is pulled, the member 24 inclines on its pivot and the upper edge 29 of the opening 25 engages the rod 15, as shown in Fig. 5. The rod is thereby cramped between the bottom edge of the opening 25 and the edge 29 and the latter bites or jams the rod so that it cannot move through the opening 25 in the direction shown by the arrow in Fig. 5, or, in other words, in the door closing direction. The force of the spring in the door closer, which impels the spindle 6 to move the arm 10 in a door closing direction, maintains the rod and latch in jamming engagement. However, movement of the rod in the other direction will release the latch and rod from jamming engagement and the member 24 will assume its normal upright position, shown in Fig. 4, the lugs 26 being of sufficient weight to overbalance the weight of the arm 27 and the string 28. The rod 15 may then slide freely through the opening 25 whereby the door closer will close the door. Thereafter, the door, upon being opened, will close automatically unless the latch and rod are again moved into jamming engagement as described.

Another embodiment of our invention is illustrated in Figs. 6 through 10. In this embodiment, the rod 15 is pivoted on two pivots 14 and 14' which permit it to pivot both horizontally and vertically. A rigid catch member 30 projects upwardly from the support 17 in place of the lugs 20 and 21 and the pivoted latch 24. This catch member 30 has an opening 31 through which the rod 15 is adapted to slide. At the top of the opening 31 there is provided a tooth 32. The rod 15 is constructed with notches 33 along its upper surface, and the tooth 32 is adapted to cooperate with these notches, as shown in Fig. 7. The teeth formed by the notches are rounded on their contact surfaces, as shown in Fig. 8, in order to properly engage the tooth 32 when the catch member 30 and the rod 15 are in jamming engagement. Pivoted to the side of the support 17 adjacent the projecting portion of the rod 15 is a trip lever 34. The string or cord 28 is secured to the outer end of this trip lever and, when the lever is pivoted by the string, the inner end 35 of the lever engages the rod 15 and forces it upwardly so that the tooth 32 engages in a notch 33 on the rod. As best seen in Fig. 7, the surfaces of the teeth formed by the notches are approximately vertical on their rearward faces and the tooth 32 has a vertical forward face. Therefore, the tooth 32 engages in the notches 33 in such manner as to

prevent movement of the rod in the direction shown by the arrow in Fig. 7, or in the door closing direction, and, as in the previous embodiment, the force of the spring in the door closer maintains the tooth in engagement with the rod. However, the surfaces of the notches and the tooth are inclined on their forward and rearward faces respectively so that, if the rod is moved in the door opening direction, there is no holding engagement and the rod drops down from the tooth whereby the door will then be shut automatically by the force of the spring in the closer. The door will continue to shut automatically after being opened until such time as the trip lever is again actuated to engage the rod with the catch member to stop the door closing motion.

Our improved device is simple in construction and adaptable for use with any door closer of the conventional type described. It is simple to operate and positively maintains the door at any desired degree of opening. By so constructing the device that it will be automatically released when the door is moved to a greater degree of opening after being held by the device, we have not only avoided the possibility of accidents or injury to persons coming into contact with the door when the present invention is in operative position, but have also provided a simple means for releasing the device from operation. The parts are simple to manufacture and easily installed and there is little likelihood of any getting out of order. The device eliminates the necessity for using wedges, chocks, foot stops or other such means for keeping a door in partially open position and, therefore, avoids potential accidents which might be caused by persons tripping over such articles. It is not only operated more quickly, but also releasable more quickly than other devices. It provides an improved and practical mechanism for use in hospitals and other places where the maintaining of a door in partially open position is highly desirable for ventilation and other reasons.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. In combination, an automatic door closer comprising a pair of arms pivotally connected together at one end with the other end of one arm being adapted to be pivotally connected to a door frame and the other end of the second arm being adapted to be pivotally connected to a door hingedly mounted on the door frame, the angular separation of said arms being dependent upon the extent to which the door is opened, and means acting upon at least one of said arms for decreasing the angular separation of said arms to urge the door in a closing direction, means for arresting closing movement of the arms comprising a rod pivotally connected to one of said arms and slidably connected to the other of said arms and a manually operable catch member mounted on the other of said arms for

preventing sliding movement of said bar with said other arm when the door is in a desired partially closed position, said catch member being releasable upon opening movement of the door.

2. In combination, an automatic door closer comprising a pair of arms pivotally connected together at one end with the other end of one arm being adapted to be pivotally connected to a door frame and the other end of the second arm being adapted to be pivotally connected to a door hingedly mounted on the door frame, the angular separation of said arms being dependent upon the extent to which the door is opened, and means acting upon at least one of said arms for decreasing the angular separation of said arms to urge the door in a closing direction, means for arresting closing movement of the arms comprising a pivoted rod slidably extending across one of said arms and adapted to be engaged by said arm to prevent closing of said door, and a manually operable catch member mounted on said arm for preventing sliding movement of said bar with said arm when the door is in a desired partially closed position, said catch member being releasable upon opening movement of the door.

3. In combination, an automatic door closer comprising a pair of arms pivotally connected together at one end with the other end of one arm being adapted to be pivotally connected to a door frame and the other end of the second arm being adapted to be pivotally connected to a door hingedly mounted on the door frame, the angular separation of said arms being dependent upon the extent to which the door is opened, and means acting upon at least one of said arms for decreasing the angular separation of said arms to urge the door in a closing direction, means for arresting closing movement of the arms comprising a rod pivotally connected to one of said arms and slidably connected to the other of said arms, a catch member mounted on the other of said arms adapted to slidably receive

said rod, and a manually operable trip lever arranged to move said rod and catch member into jamming engagement when the door is in a desired partially closed position, said rod and catch member being automatically releasable from jamming engagement upon opening movement of the door.

4. In combination, an automatic door closer comprising a pair of arms pivotally connected together at one end with the other end of one arm being adapted to be pivotally connected to a door frame and the other end of the second arm being adapted to be pivotally connected to a door hingedly mounted on the door frame, the angular separation of said arms being dependent upon the extent to which the door is opened, and means acting upon at least one of said arms for decreasing the angular separation of said arms to urge the door in a closing direction, means for arresting closing movement of the arms comprising a rod having a serrated edge and pivotally connected to one of said arms, a catch member mounted on the other of said arms for slidably receiving said rod and having a tooth adapted to engage the serrated edge of the rod, and a manually operable trip lever adapted to move the rod and catch member into jamming position with said tooth of the catch member engaging said serrated edge of the rod, said rod and catch member being automatically releasable from jamming engagement upon opening movement of the door
